Patented Aug. 24, 1971

221,590

MACHINING CENTER

Charles A. Larsen, Union Grove, Daniel J. Mousseau,
Racine, and Kenneth M. Boutell, Franksville, Wis.,
assignors to Gorton Machine Corporation, Racine,
Wis.

Filed June 22, 1970, Ser. No. 23,589

Term of patent 14 years

Int. Cl. D15—99

U.S. Cl. D54—14

FIG. 1.

Des. 221,590

PAGE 2

FIG. 2.

Des. 221,590

PAGE 3

FIG. 4.

FIG. 1 is a perspective view of a machining center showing the front and right side thereof illustrating our new design;

FIG. 2 is a front view in elevation of the machining center;

FIG. 3 is a right side view in elevation of the machining center; and,

FIG. 4 is a top plan view of the machining center. The left and rear sides, not shown, of the machining center being substantially plain.

We claim:

The ornamental design for a machining center, substantially as shown and described.
